(57) **CLAIM**

The ornamental design for a support for a computer-related accessory, as shown and described.

DESCRIPTION

FIG. 1 is a perspective view of a support for a computer-related accessory, which embodies the design, shown with respect to a wall-mounted monitor;

FIG. 2 is a right side view thereof;

FIG. 3 is a top view thereof;

FIG. 4 is a perspective view support for a computer-related accessory, shown with respect to a worksurface-mounted monitor;

FIG. 5 is a right side view thereof;

FIG. 6 is a top view thereof;

FIG. 7 is a perspective view support for a computer-related accessory, shown with respect to a keyboard tray;

FIG. 8 is a right side view thereof; and,

FIG. 9 is a top view thereof.

The broken line showing of environmental structure forms no part of the claimed design.
